UNITED STATES PATENT OFFICE

155,463

DESIGN FOR A JEWELED LADY'S STOCKING
OR THE LIKE

Ellen Troy, New York, N. Y.

Application October 20, 1947, Serial No. 142,023

Term of patent 14 years

(CL. D47—7)

To all whom it may concern:

Be it known that I, Ellen Troy, a citizen of the United States of America, residing at New York, county and State of New York, have invented a new, original, and ornamental Design for a Jeweled Lady's Stocking or the like, of which the following is a specification, reference being made to the accompanying drawing, forming a part thereof.

In the drawing:

Fig. 1 is a side-elevational view of a lady's jeweled stocking, showing my new design.

Fig. 2 is an enlarged fragmentary sectional view, taken along line 2—2 of Fig. 1.

I claim:

The ornamental design for a jeweled lady's stocking or the like, substantially as shown.
ELLEN TROY.
